STAND-UP DISPENSING TUBE

Donald Howard Goff, Mountainside, N.J., assignor to
American Can Company, New York, N.Y., a corpora-
tion of New Jersey

Filed Sept. 1, 1967, Ser. No. 8,476

Term of patent 14 years

U.S. Cl. D9—194
Int. Cl. D9—04

FIG. 1

FIG. 2

FIGURE 1 is a front elevation of a stand-up dispensing tube showing my new design, the side opposite being similar except plain and unornamented;

FIGURE 2 is a side elevation thereof the side opposite being a mirror image thereof.

The essential features of the design reside in the full line portions of the drawing, the broken lines pictorially representing a mound of ice cream.

The end view surface of the tube cap of circular configuration is plain and unornamented.

I claim:

The ornamental design for a stand-up dispensing tube, substantially as shown and described.
